Paul Stahl.

UNITED STATES PATENT OFFICE.

KARL STAHL, OF FRIEDRICHSHAFEN, GERMANY, ASSIGNOR TO THE FIRM LUFT-SCHIFFBAU ZEPPELIN GESELLSCHAFT MIT BESCHRANKTER HAFTUNG, OF FRIEDRICHSHAFEN, GERMANY.

SIGNALING BELL.

Application filed June 28, 1920. Serial No. 392,606.

To all whom it may concern.

Be it known that I, KARL STAHL, a citizen of the German Empire, residing at Friedrichshafen a/B., Germany, have invented 5 certain new and useful Improvements in Signaling Bells, of which the following is a specification.

My invention refers to signaling bells with mechanical operation at a distance and 10 more especially to the attachment of the parts serving to work the mechanism for operating at a distance, as well as the constructions of the signaling device proper.

It is a well-known fact that all signaling 15 bells worked by a traction wire very easily fail when worked from a large distance. The reason for this is found in the more or less considerable sagging of the traction wire which, besides on the distance between 20 the points of support of the traction elements and the dead weight of the traction wire, depends very much on the variations of temperature. On the other hand the reliability in working of these parts is then 25 particularly endangered if they are included in a body constantly in motion and subjected permanently to concussions, such as an air-ship. For the traction wires not kept taut, easily begin to oscillate owing 30 to which a spontaneous striking of the bells can often not be impeded. Moreover, the signaling bells with traction wire motion hitherto known, generally have a rather short stroke which renders it very difficult 35 to give a clear signal.

The said draw-backs also adhere to such signaling bells where the working of the bell takes place through the agency of an endless traction wire. Besides the facts that 40 this type of signaling bells cannot be applied with advantage everywhere owing to their complicated traction wire guiding appliances and their costs of construction, their expensiveness in material and their 45 weight are comparatively speaking, very high. This latter point proves especially disadvantageous in the construction of air-ships where a plurality of such signaling apparatus are always fitted in.

50 It is the object of the present invention to create a mechanical signaling apparatus which differs from those hitherto known by the fact that the sagging of the traction wires serving to operate it at a distance, is 55 reduced to a minimum which no longer

endangers the reliability of working. Furthermore it is its endeavor to make the employment of signaling bells with long traction wires possible even under the very unfavorable conditions of space in large aircraft. More especially it is its object to ensure the production of long strokes of the bell or long-sustained ones, respectively with a single giving of the signal.

The object of the invention therefore consists of a signaling bell in which, as striking bodies, several centrifugal hammers are made to serve which rotate outside the bell and whose common shaft is developed as a rope drum for a traction wire. The traction wire being wound up on a drum, a long way of displacement which neutralizes possible sagging, can easily be obtained for the traction wire in giving signals. The rotating centrifugal hammers, however, owing 70 to the quick repeated rotation of the shaft, strike the bell repeatedly, thus ensuring a long-sustained forcible signal. The traction wire can be made endless. Particular advantages are, however, offered by a signaling bell in which the shaft carrying several rotating centrifugal hammers, is taken back to its "off" position by releasing a powerful spiral spring of many turns which is put under fresh tension by each pulling of the 75 traction wire. For in this manner a large way for the hammers is ensured under elimination of the traction wire return, whilst the powerful spring can be simultaneously arranged in a spring casing and is 80 here removed from all influences of the 85 weather, besides consuming very little space.

The connection of the centrifugal hammers with the shaft can be chosen according to liking, but special advantages are offered by an arrangement in which, in accordance with the invention, the hammer arms bearing the hammer disks proper on the one hand and fitted on a disk-like enlargement of the driving shaft on the other hand, possess ample play at least in the one point of connection, or link respectively, so that even with the hammer arms directed radially, rebounding of the hammer disks from the bell is made possible. For in this manner a pure and clear sound of the bell is called forth even with the quickest motion of the traction wire, as the hammer disks striking on the bell, can not only give way 100 in the direction of the periphery of the 105 110

centrifugal circle together with the hammer arms, but also, if necessary, alone and in any desirable direction. By this means not only the way and the time for the hammer to fly back from the bell is reduced,

5 but its immediate return into the striking position is considerably hastened.

The drawing attached to this specification and forming part thereof, illustrates 10 by way of example a signaling bell arrangement in accordance with my invention in a purely diagrammatical manner.

Fig. 1 of the drawings shows an axial cross-section of a signaling bell for operation by traction wire, taken on the line 1—1 in Fig. 2.

Fig. 2 is the pertinent top view, partly in cross-section.

A bell A is screwed, in a manner already 20 known as such, to a support C with a pillar-bolt B inserted in between. A casing D closed nearly all around, is fastened on the support C removably and in such a manner that the part of the bell to be struck, projects in to the casing a little through an aperture d' provided in the casing D. A shaft E is fitted rotatably in bearings in the sides of the casing D approximately on a level with the rim of the bell. The shaft 25 E besides the rope drum F is provided with 2 disks G and a lug H. These parts are connected rigidly with the shaft. To the rope drum F a wire cable J is attached and wound around the drum several times with 30 its loose end. Through an aperture d^4 provided in the casing D it is then led to a commander's stand situated at some distance. Between the disks G several centrifugal hammer arms K are linked on. In 35 their link parts they are provided with slots K' and in their free fork-shaped ends they each contain a hammer disk L which is fitted on its gudgeon K² with a considerable amount of play. A spiral spring M, contained in a spring casing N, is suspended 40 from the lug H. The spring casing N is secured to the casing D. By pulling the wire I the axle E is rotated and the hammers L driven outwards by centrifugal ac-

tion strike the bell. On the pull on the 50 wire being released the spring M causes the axle to rotate in opposite position and to wind up the wire.

I wish it to be understood that I do not desire to be limited to the exact details of 55 construction shown and described, for obvious modifications will occur to a person skilled in the art.

I claim:

1. In a device of the kind described in 60 combination, a bell, an axle outside said bell, a hammer connected with said axle so as to rotate and to touch said bell when said axle is rotated, and a rope drum on said axle.

2. In a device of the kind described in 65 combination, a bell, an axle outside said bell, a hammer connected with said axle so as to rotate and to touch said bell, when said axle is rotated, and a rope drum and a 70 spiral spring on said axle.

3. In a device of the kind described in 75 combination, a bell, an axle outside said bell, a hammer connected with and radially displaceable with relation to said axle so as to rotate and to touch said bell when said axle is rotated, and a rope drum on said axle.

4. In a device of the kind described in 80 combination, a bell, an axle outside said bell, a hammer connected with said axle so as to rotate and to touch said bell when said axle is rotated, a rope drum on said axle and a stationary casing surrounding said axle, hammer and rope drum and presenting only two passages one for part of 85 the bell and the other for the rope connected with said rope drum.

5. In a device of the kind described in 90 combination, a bell, an axle outside said bell, two discs on said axle, two diametrically arranged pins connecting said discs, a slotted link on each pin and a roller at one end of each link adapted when set revolving, to contact with said bell and a 95 rope drum on said axle.

In testimony whereof I affix my signature.

KARL STAHL.
